[57] CLAIM

The ornamental design for a desk drawer organizer, as
shown and described.

DESCRIPTION

FIG. 1 is a perspective view of a desk drawer organizer
in accordance with the present invention;

FIG. 2 is a front elevational view thereof;

FIG. 3 is a side elevational view thereof;

FIG. 4 is a top plan view thereof; and,

FIG. 5 is a rear elevational view thereof.

The bottom of the article is plain and unornamented.

*Fig. 1**Fig. 2**Fig. 3**Fig. 4**Fig. 5*
